UNITED STATES PATENT OFFICE.

EARNEST WASHINGTON AND HENNING ANDERSON, OF FARIBAULT, MINNESOTA.

WRENCH.

1,152,064.

Specification of Letters Patent. Patented Aug. 31, 1915.

Application filed February 16, 1915. Serial No. 8,473.

To all whom it may concern:

Be it known that we, EARNEST WASHINGTON and HENNING ANDERSON, citizens of the United States, residing at Faribault, in the 5 county of Rice and State of Minnesota, have invented certain new and useful Improvements in Wrenches, of which the following is a specification.

This invention relates to certain new and 10 useful improvements in wrenches and more particularly to that class of wrenches in which provision is made for adjustment to enable the jaws to grip nuts, pipes, or other objects of various sizes, and in which provision is also made for quick release when 15 desired.

The present invention has for its objects among others to provide an improved wrench having a simple and cheap, yet reliable and 20 efficient form of release mechanism whereby the nut or other object may be quickly and automatically released and yet which will firmly hold the nut or other object during the manipulation of the wrench. In 25 the form herein shown there is provided an oscillatory adjustable jaw, supported upon a spring disposed substantially at its mid center so as to allow the jaw to rock for the purpose of release, provision being made 30 for holding the jaw against such movement while the wrench is in use.

We aim further at improvements in the details of construction whereby we obtain a very strong and durable wrench at small 35 cost and of light weight. Also one in which the parts are readily assembled and as easily disassembled for the purpose of repairs or other purposes.

Other objects and advantages of the invention will hereinafter appear, and the novel features thereof will be specifically defined by the appended claims.

The invention, in its preferred form, is clearly illustrated in the accompanying 45 drawings, which, with the numerals of reference marked thereon, form a part of this specification, and in which—

Figure 1 is a side elevation of our improved wrench, with a portion of the shank 50 broken away. Fig. 2 is a cross section on the line 2—2 of Fig. 1, looking in the direction of the arrows. Fig. 3 is a longitudinal section, as on the line 3—3 of Fig. 1, looking in the direction of the arrows. Fig. 4 is a perspective view of the movable 55 jaw, removed.

Like numerals of reference indicate like parts throughout the several views.

Referring to the drawings 1 designates the shank which may be of any desired 60 length, provided with a handle or hand grip of usual form, not shown, the said shank carrying the fixed jaw 2, preferably provided upon its inner face with serrations as at 3. This shank is further provided with teeth 4 with which engages the adjusting screw or worm 5, as seen in Figs. 1 and 3, for the purpose of adjusting the movable jaw to and from the fixed jaw, in the usual manner. At the junction of the 70 shank and stationary jaw we provide the portion 6 which not only serves to reinforce the device at this point, but also serves as a bearing for the nut or other object to be grasped by the jaws.

75 7 is a housing or the like through which the shank passes freely and in bearings 8 and 9 in this housing the pins 10 and 11 are mounted, and on these pins the screw or worm is free to revolve. The housing 7 80 has the extensions 12 between which is formed the chamber 13, as seen best in Fig. 3, and in which the movable jaw 14 is retained. This jaw is formed with the extension 15, as seen in Figs. 1, 3 and 4, to 85 engage the side of the nut or other object being grasped, and the acting face of this movable jaw is preferably slightly concave as shown and this face is provided with serrations 16, for an obvious purpose.

90 The movable jaw 14 is normally pressed outward, that is, toward the fixed or stationary jaw 2, by means of a spring 17, seated at its ends in pockets or the like 18 and 19 in the under side of the said movable jaw 95 and the bottom wall of the extension of the housing as seen clearly in Fig. 3. This spring is disposed at substantially the center of the movable jaw and while tending it to force the same outward it permits of rolling 100 or rocking motion of the said jaw, for a purpose soon to be described.

Projecting laterally from the movable jaw are the pins 20 and 21, which pins project from both sides of the jaw and are loosely 105 received in the slots 22 and 23 respectively in the side extensions of the housing as seen best in Fig. 1. As seen in Fig. 1, the slot 22 extends substantially parallel with the shank and at its end nearest the acting face 110 of the movable jaw it has a right angled extension 24 extending toward the shank. As

will also be seen from Fig. 1 the slot 23 has a main portion extending substantially in the direction of the length of the shank but upon the arc of a circle, and at the end thereof nearest the acting face of the movable jaw is extended at an angle as seen at 25 which angled portion extends not only toward the shank but also outward toward the fixed jaw.

10 As seen best in Fig. 1 the slots 22 and 23 are reinforced by ribs or the like 26 and 27 surrounding the said slots respectively.

The operation will be readily understood. The wrench is applied to the nut or other 15 article to be grasped, in the usual way. A movement of the wrench in one direction, that indicated by the curved arrow in Fig. 1, has a tendency to tighten the grip of the movable jaw on the article which it grips.

20 Movement of the wrench in the opposite direction releases the movable jaw from the object between the jaws, the said movable jaw rocking on its spring 17 and the pins 20 and 21 moving in the angled portions of the 25 slots from the position in which they are shown in Fig. 1 and riding down said portions into the longitudinal portions of the slots, allowing the movable jaw freedom of movement so that the wrench slips off of the 30 article which it had engaged. The spring is so disposed as to normally force and hold the parts in the position in which they are seen in Fig. 1, in full lines.

From the above it will be seen that we 35 have devised a simple, cheap and durable and efficient wrench, convenient in use, well adapted for automobile work as well as for other purposes, and while the structural embodiment of the invention as hereinbefore 40 set forth is what we at the present time consider preferable, it is evident that the same is subject to changes, variations and modifications in detail, proportion of parts, etc., without departing from the spirit of 45 the invention or sacrificing any of its advantages. We, therefore, do not wish to restrict ourselves to the exact construction and arrangement of parts herein disclosed, but 50 reserve the right to make such changes, variations and modifications as come properly within the scope of the protection prayed.

What is claimed as new is:—

1. In a wrench, a shank, a fixed jaw, a movable jaw loosely rockingly mounted, a spring forming its support and normally 55 forcing the same toward the fixed jaw and guiding means upon opposite sides of said support for guiding the movable jaw in its movements and locking it against movement. 60

2. In a wrench, a shank, a fixed jaw, a rockingly-mounted movable jaw, a casing for the movable jaw, having angular slots upon opposite sides of the fulcrum of the movable jaw, and means on the movable 65 jaw working in said slots. 70

3. In a wrench, a shank, a fixed jaw, a rockingly-mounted spring-supported movable jaw, a housing for the movable jaw having slots upon opposite sides of the fulcrum of the movable jaw with angular portions disposed at an angle to the length of the shank, and means on the movable jaw working loosely in said slots. 75

4. In a wrench, a shank, a stationary jaw, a housing movable on the shank and a spring supported movable jaw rockingly mounted within the housing and bodily movable toward and from the fixed jaw and relatively to the housing and angular slots 80 upon opposite sides of the fulcrum of the movable jaw, said movable jaw having lateral projections coöperating with said slots to guide the jaw and to lock the same. 85

5. In a wrench, a shank, a fixed jaw, a rockingly mounted movable jaw fulcrumed upon a spring support, a casing for the jaw and connections between the movable jaw and casing embodying angular slots upon opposite sides of the fulcrum of the movable 90 jaw, and lateral pins on the movable jaw engageable in said slots whereby the wrench may be turned one way to grip an object and turned the other way to be released from the object so that a new grip may be had. 95

In testimony whereof we affix our signatures in presence of two witnesses.

EARNEST WASHINGTON.
HENNING ANDERSON.
